(57) **CLAIM**

The ornamental design for a book cover, as shown and described.

DESCRIPTION

FIG. 1 is a top plan view of a book cover showing our new design, the bottom plan view being a mirror image thereof; and,

FIG. 2 is a perspective view thereof.

The right and left side elevation views, and the front and rear elevation views form no part of the claimed design.

1 Claim, 2 Drawing Sheets

FIG. 1

FIG. 2
